UNITED STATES PATENT OFFICE.

WALTER HAY, OF SEVILLE, OHIO, ASSIGNOR OF ONE-HALF TO EMERSON M. HOTCHKISS, OF WATERBURY, CONNECTICUT.

MOTION-CONVERTING MECHANISM.

SPECIFICATION forming part of Letters Patent No. 624,931, dated May 16, 1899.

Application filed April 4, 1898. Serial No. 676,296. (No model.)

To all whom it may concern:

Be it known that I, WALTER HAY, a citizen of the United States of America, and a resident of Seville, in the county of Medina, State 5 of Ohio, have invented certain new and useful Improvements in Motion-Converting Mechanism, of which the following is a specification.

My invention relates to improvements in engine construction, more particularly adapted for motors, pumps, compressors, &c., which comprise tandem-coupled cylinders and a crank-shaft arranged in operative connection with the reciprocating pistons of said cylinders; and the object of my improvement is to relieve such pistons of the thrusts or strains which heretofore have been experienced in the operation thereof. I attain this object substantially in the manner and by the means as illustrated in the accompanying drawings, 20 in which—

Figure 1 represents a part-sectional and part-exterior view of a pair of single-acting tandem-arranged yoke and crank operating or operated cylinders provided with the improvements above referred to. Fig. 2 is a partial plan view of same. Fig. 3 is a cross-sectional view of same on line *xx*. (See Fig. 1.) Fig. 4 represents a part-sectional and part-exterior view of another pair of tandem-arranged 30 yoke, connecting-rod, and crank operating or operated cylinders improved in like manner. Fig. 5 illustrates a part-plan and part-sectional view of same. Fig. 6 is a cross-sectional view on line *yy*. (See Fig. 4.)

Like letters of reference denote like parts in the drawings and specification.

The essential feature of my invention consists in the application of integral differential rollers in connection with elementary engine 40 construction of such or similar type as shown in the accompanying drawings.

In the construction illustrated in Figs. 1, 2, and 3, A A' represent partial views of the working cylinders, between which is placed the crank-shaft B. The yoke C is adapted for operative connection with the pistons D of said cylinders with and by the intervention of the crank-pin E of said shaft. The rods F F' of the pistons are hinged to said yoke, as 45 seen at *a a*, while the pin E is embraced by blocks *b b*, which move within said yoke.

(See Fig. 1.) Parallel to or with the center line of the cylinders extend the guides *cc* from each side of the yoke. At *c* said guides are shown united simply to render the structure more rigid. (See Figs. 1 and 3.) Adjustably attached to each side of the cylinders, near the end thereof, is shown a bifurcated bracket G, between which and the above-mentioned guides is placed a roller H, which 55 consists of the major member *d* and the minor members *ee*. The brackets are adjusted in relation to the yoke-guides to maintain the major member *d* of the rollers in contact with the guides and the minor members *e* in contact with the inner faces *f* of the brackets. Under such conditions the rollers will move 60 in unison with the yoke-guides; but the ratio of the linear travel of the rollers to that of the yoke is identical with the difference in circumference between the major rollers and the minor ones. If thus, for instance, the stroke 65 of the yoke equals the circumference of the roll part *d*, then the rollers proper will move within a distance equal to the circumference 70 of the minor rollers *ee*. Only a limited movement of the rollers is required to answer the purpose of subduing friction to a minimum. The conversion of reciprocating motion of the piston into rotary motion of the crank-shaft 75 causes more or less severe angular thrusts upon the yoke guide-bearings; but with this improvement where the bearings consist of compound rollers there is no friction which needs lubrication. Also strains upon the piston 80 cannot exist, since same are borne by the rollers.

In providing a hinged or loose connection for the piston-rods near the center of the yoke it is obvious that a possible displacement of the yoke itself can have but little or no detrimental effect upon the pistons. Yokes or even cross-heads, guided between or upon compound rollers arranged substantially as shown, avoiding strains and requiring no lubrication, constitute an essential feature in engine constructions for motor-carriages, &c.

In the construction illustrated in Figs. 4, 5, and 6 the rods I are employed for connection of the shaft E' with the outer ends *g* of the yoke C'. The roller-retaining brackets are embodied in continuous bars G', reach-

ing from one cylinder end to the other, and the piston-rods F are connected with the yoke substantially as those shown in Fig. 1.

It is evident that compound rollers are useful in converting reciprocating motion into rotary motion as well as in converting rotary motion into reciprocating motion, and such means may be applied in many similar kinds of engine constructions without departing from the nature of my invention.

What I claim, and desire to secure by Letters Patent, is—

1. In engine constructions the combination with tandem-arranged cylinders and the pistons thereof of a yoke connecting with the rods of said pistons, a crank-shaft rotated by said yoke, guides extending from each side of said yoke, adjustable and yieldingly-supported brackets or bars retained normally in parallel position to said guides and integral

differential rollers establishing rolling contact with and of said guides and brackets or bars for the purpose as set forth.

2. The combination with tandem-arranged cylinders and the pistons thereof of a piston-rod connecting guide-yoke, connecting-rods and a crank-shaft, adjustable and yieldingly-supported parallel bars or brackets and differential rollers, the large and small members of said rollers being respectively in contact with said guide-yoke and the said parallel bars to relieve the pistons of undue strains substantially in the manner as and for the purpose set forth.

Signed by me, at Cleveland, Ohio, this 28th day of March, 1898.

WALTER HAY.
